SAFETY RAZOR BLADE SHARPENER

Joseph Levine, New York, N. Y.

Application July 12, 1932. Serial No. 622,081

5 Claims. (Cl. 51—211)

This invention relates to new and useful improvements in a safety razor blade sharpener.

The invention has for an object the construction of an article as mentioned which is characterized by 5 glass material formed into a semi-cylindrical container having a cover partially closing the top and extending from the rear edge and having a central bent-in portion for the thumb providing for the convenient holding of the device. Furthermore, as another object it is proposed to 10 close the rear end of said semi-cylindrical container to serve as a reinforcement for adding rigidity.

Another one of the objects is the provision of 15 corrugations upon the inner face of said cylindrical container to provide sharpening elements for the blade.

Furthermore, this invention proposes the provision of means for varying the degree of said 20 corrugations to vary the sharpening qualities of said device.

Another one of the objects of this invention is the construction of a device as mentioned which is simple and durable and which may be manufactured and sold at a reasonable cost. 25

For further comprehension of the invention, and of the objects and advantages thereof, reference will be had to the following description and accompanying drawing, and to the appended claims 30 in which the various novel features of the invention are more particularly set forth.

In the accompanying drawing forming a material part of this disclosure:

Fig. 1 is a perspective view of a device constructed according to this invention. 35

Fig. 2 is a sectional view taken on the line 2—2 of Fig. 1.

Fig. 3 is a perspective view of a modified form of the invention. 40

Fig. 4 is a fragmentary sectional view taken on the line 4—4 of Fig. 3.

Fig. 5 is a view similar to Fig. 2 but illustrating a modification of the invention. 45

Fig. 6 is a transverse sectional view taken on the line 6—6 of Fig. 5.

The safety razor blade sharpener according to this invention comprises an integral mass of glass formed into a semi-cylindrical container 10 having a cover 11 partially closing the top there- 50 of and extending from the rear to a point midway to the front. Along the central longitudinal line of this cover there is formed a concaved portion 12 which constitutes a rest or grip for the thumb when the device is held in the hand. The cy- 55 lindrical container is formed with a closed back

13 serving to give it greater rigidity. The inner surface of the cylindrical container is formed with a plurality of corrugations 14 designed so as to facilitate the sharpening of the edges of the blade. 60

In Fig. 1, a blade 15 is shown resting within the cylindrical container and the arrows 16 indicate the direction of motion of the blade to obtain sharpening. The concaved portion 12 also serves as a guide to press a finger inserted within said 65 container down against the blade to be sharpened. The top side of the finger will engage against the convexed inner side of the portion 12 and so provide pressure to bow the blade during its motion back and forth within the inner surface 70 of the semi-cylindrical member.

In the way of an explanation it is pointed out that if the edges of the razor are bent straight the blade will be sharper and better able to cut the hair. The corrugations so bend the roughened 75 edges of the blade during its motion back and forth within the cylindrical container. The blade must be tightly bowed against the inside of the container so that the edges are in tension against the corrugations. A smooth surface within the 80 container would work, but it has been found that corrugated surfaces are more suited in that the pressure against the edges of the blade is greater.

In the form of the invention disclosed in Figs. 3 and 4, the device comprises sheet material in 85 the form of a semi-cylindrical portion 27, a partially closed top 28 having a central longitudinal depressed portion 29 for the thumb and for guiding the finger which moves the blade over the inner surface of said semi-cylindrical container, 90 and back cover 30. A sharpening element 31 which preferably should be made from glass is of the shape so as to fit snugly within the semi-cylindrical portion 27. The glass member 31 is formed with a plurality of corrugations 32 95 against which the edges of a blade may be pressed and moved as previously described to produce sharpening. A pair of springs 33 are attached upon the bottom of the partial cover 28 and engage against small recesses 34 formed in the edges 100 of the glass member 31 for holding the glass member detachably in place. The arrangement allows for the withdrawal and substitution of the corrugated member. 105

In Figs. 5 and 6 a modification of the invention has been disclosed in which a means is provided for varying the degree of corrugations to vary the sharpening quality of the device and so best adapt it for particular blades or for the particular manner in which one moves the blade 110

within the container. In detail this means comprises an outer shell 17 formed with a plurality of ribs 18 engaging through slots 19 in the cylindrical container. This outer shell is held against 5 complete displacement by lug elements 20 projecting from the container and engaging the edges of the shell. The ribs 18 are of such height that normally with the shell extended they lay within the surfaces of the container, but when the shell 10 is moved inwards they protrude.

A means is provided for locking the shell 17 in the extended position and comprises a shell 21 within the thumb bent portion 12 and which is connected with rods 22 extending through the 15 container and provided with hooks 23 on the outer ends adapted to engage beneath the edges of the shell 17 when the shell 21 is depressed and so hold the shell 17 against moving inwards. Springs 24 normally urge the rods 22 into inoperative positions.

A blade may be sharpened in the device shown in Figs. 3 and 4 with the ribs 18 retracted or extended as desired. When used with the ribs 18 extended it is necessary that the shell 17 be 25 pressed tightly against the outside of the cylindrical container and so held.

While I have illustrated and described the preferred embodiment of my invention, it is to be understood that I do not limit myself to the precise construction herein disclosed and the right 30 is reserved to all changes and modifications coming within the scope of the invention as defined in the appended claims.

Having thus described my invention, what I 35 claim as new, and desire to secure by United States Letters Patent is:—

1. A safety razor sharpener, comprising a semi-cylindrical container, a partial cover on the top thereof extending from the rear and having a bent portion for the thumb, a closed back, corrugations within said container, and means for varying the degree of corrugations to vary the sharpening qualities of said device comprising a rib element adjustable on said container in a 40 manner that said ribs may be projected from the corrugated surface.

2. A safety razor sharpener, comprising a semi-cylindrical container, a partial cover on the top thereof extending from the rear and having a bent portion for the thumb, a closed back, corrugations within said container, and means for varying the degree of corrugations to vary the sharpening qualities of said device, comprising an outer shell with ribs extending into slots 50 formed in said container, means for slidably holding said outer shell relative to said container, and means for locking the outer shell in an extended position.

3. A safety razor sharpener, comprising a semi- 60

cylindrical container, a partial cover on the top thereof extending from the rear and having a bent portion for the thumb, a closed back, corrugations within said container, and means for varying the degree of corrugations to vary the sharpening qualities of said device, comprising an outer shell with ribs extending into slots formed in said container, means for slidably holding said outer shell relative to said container, and means for locking the outer shell in an extended position, comprising a shell within said thumb groove, rods projecting from said latter mentioned shell and extending through said container to the vicinity of the edges of said outer shell, and resilient means urging said rods into positions in which the outer shell is free.

4. In a safety razor blade sharpener, a semi-cylindrical container, a semi-cylindrical sharpening element engaging within said container and adapted to sharpen the edges of a safety razor blade when the blade is placed substantially longitudinal of the axis of said sharpening element and moved transversely back and forth against the inner surface thereof, a cover transversely across the top edges of said semi-cylindrical container 100 and having a central curved portion with a center of curvature substantially coinciding with the axis of said semi-cylindrical container for guiding the finger when moving the blade transversely, and a pair of springs attached upon the bottom side of said cover, more particularly upon the straight portions thereof and engaging small recess in the edges of said semi-cylindrical sharpener element to hold the latter element detachable in place.

5. In a safety razor blade sharpener, a semi-cylindrical container, a semi-cylindrical sharpening element engaging within said container and adapted to sharpen the edges of a safety razor blade when the blade is placed substantially longitudinal of the axis of said sharpening element and moved transversely back and forth against the inner surface thereof, a cover transversely across the top edges of said semi-cylindrical container and having a central curved portion with 115 a center of curvature substantially coinciding with the axis of said semi-cylindrical container for guiding the finger when moving the blade transversely, and a pair of springs attached upon the bottom side of said cover, more particularly upon the straight portions thereof and engaging small recess in the edges of said semi-cylindrical sharpener element to hold the latter element detachable in place, said pair of springs being arranged in the longitudinal and engaging against 125 the longitudinal edges of said semi-cylindrical sharpening element.
